UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 15,102, dated June 24, 1884.

Application filed May 12, 1884. Term of patent 3⁴ years.

To all whom it may concern:

Be it known that I, LOUISE TULLY, of the city, county, and State of New York, have invented and produced a new and original Design for a Pattern of a Girl's Costume, (numbered 9,214;) and I do hereby declare that the engraved prints accompanying this specification convey to any one accustomed to using paper patterns a clear understanding of how to a garment made up by the pattern will appear.

The design shows loose-fitting fronts exhibiting a fastening all the way down; a half-fitted back; a gathered skirt; a full sash-drapery, exhibiting draping plaits in the left side

and a cross-piece over the crossing of its ends at the back; a plain left side-drapery falling over the sash; coat-sleeves, and a standing collar.

What I claim as my invention, and desire to secure by Letters Patent, is—

The design for a girl's costume, as shown in the engraved prints accompanying this specification.

LOUISE TULLY.
